TUNING DEVICE FOR WIND MUSICAL INSTRUMENTS

Filed May 17, 1930

UNITED STATES PATENT OFFICE

ALLEN LOOMIS, OF ELKHART, INDIANA, ASSIGNOR TO C. G. CONN, LTD., OF ELKHART, INDIANA, A CORPORATION OF INDIANA

TUNING DEVICE FOR WIND MUSICAL INSTRUMENTS

Application filed May 17, 1930. Serial No. 453,845.

This invention relates to wind musical instruments of the reed type, and particularly to clarinets.

The principal object of my invention is to provide an improved combined tuning device and joint for connecting the mouthpiece and body of a reed musical instrument.

Another object of the invention is to provide an improved tuning barrel joint for metal clarinets, and the like, wherein a very effective, and durable non-advancing adjusting nut is incorporated.

Other objects of the invention are mentioned and described herein.

The preferred embodiment of my invention is illustrated in the accompanying drawings, wherein

Figure 1 is an exterior view in elevation showing the assembled tuning barrel joint;

Fig. 2 is a similar view in section;

Fig. 3 illustrates an exterior elevational view of an assembly of the mouthpiece holder, the guide member, the inside tubular slide, and the retaining or thrust ring for the adjusting nut;

Fig. 4 is an exterior elevational view of the outside tubular sliding sleeve;

Fig. 5 is a perspective of the same member;

Fig. 6 is a sectional elevational view of the adjusting nut;

Fig. 7 is a section taken on line 7-7 of Fig. 2, and

Fig. 8 is an enlarged sectional fragment illustrating the connections between the parts which form the complementary flange and groove connection between the adjusting nut and the mouthpiece holder.

Similar numerals of reference indicate like parts throughout the several views on the drawings.

Referring now to the drawings, and especially to Figures 1 and 2 wherein an assembly of my improved tuning barrel joint is illustrated, the device comprises, generally, the tubular mouthpiece receiver or holder 1, the ring-like pronged guide member 2 rigidly secured thereto, the inside tubular slide 3, the outside tubular sliding member 4 which slidably encompasses the

inside slide and which is actuated by the rotatable tubular adjusting nut 5, and the retaining ring 6 which takes the thrust of the adjusting nut when the latter is rotated.

The sleeve 4 may be provided with a cork sleeve 7 which is adapted to fit and seal within the tubular end of a clarinet, or like instrument. The tubular upper end of the guide member 2 is provided with an annular right angular flange 8 which projects outwardly therefrom and which may be soldered to the lower end of the mouthpiece holder 1, said guide member being provided with a pair of opposed prongs 9 and 10 which extend longitudinally of the slide 3 into the interstices of a similar pair of opposed prongs 11 and 12 formed on the end of the tubular sliding sleeve 4.

The numeral 5 indicates the tubular adjusting nut which encompasses one end of the sleeve 4 and the prongs of elements 2 and 4, there being a screw thread connection at 13 between one end of the bore of said adjusting nut and the exterior of member 4 adjacent the base of the prongs 11 and 12. The opposite end of the nut 5 is provided with an integral annular right angular outwardly extending flange 14 which is rotatably arranged in the annular circumferential bearing groove 15 which is formed between the flange 8 of member 2 and the annular inwardly projecting thrust flange 16 formed on the retaining ring 6 which is mounted upon the holder 1.

The retaining or thrust ring 6 may be screw threaded to the exterior of the holder 1 at 17 the thrust flange 16 thereof extending inwardly to a point below the guide flange 8, and solder may be applied to said screw thread connection to effect a more rigid connection thereat. The ring 6 may be provided also with an annular interior shoulder 18 which fits snugly against the flange 8, adjacent the outer periphery of the latter, of member 2 to effect the proper clearance between the adjusting nut flange 14 and the walls of the groove 15 in which said nut flange is rotatably arranged and retained. Preferably the slide 3 is soldered in the bore 100

of member 2, the upper end thereof terminating flush with the face of the guide flange 8 of member 2.

It will be evident from the foregoing description and arrangement of the parts of my improved tuning barrel joint that rotation of the adjusting nut 5 will cause longitudinal sliding movement of the sleeve 4, whereby the air column within the joint unit 10 may be lengthened or shortened at will, according to the direction of rotation of said nut, thereby altering the tone of the instrument.

I claim:

1. A combined tuning device and joint of the character described comprising a tubular mouthpiece holder, a ring-like guide member provided with a flange which is rigidly mounted on said holder, a tubular slide member rigidly mounted in said guide member, a tubular member slidably encompassing said slide member and slidably connected with said guide member, a tubular rotatable adjusting nut, a complementary spiral connection between said adjusting nut and the tubular slide member, and a complementary flange and groove connection between said adjusting nut and the mouthpiece holder to prevent longitudinal movement of said nut when the latter is rotated, said connection including a ring-like thrust member which is connected with the exterior of said mouthpiece holder.

2. A combined tuning device and joint of the character described comprising a tubular mouthpiece holder, a ring-like guide member of lesser diameter than said holder and provided with a flange which is rigidly mounted on said holder, a tubular slide member rigidly mounted in said guide member bore, a tubular member slidably encompassing said slide member and slidably connected with said guide member, a tubular rotatable adjusting nut, a complementary spiral connection between said adjusting nut and the tubular slide member, and a complementary flange and groove connection between said adjusting nut and the mouthpiece holder to prevent longitudinal movement of said nut when the latter is rotated, said connection including a member encompassing said mouthpiece holder and an annular inwardly projecting thrust flange integral therewith.

3. A combined tuning device and joint of the character described comprising a tubular mouthpiece holder, a ring-like guide member of lesser diameter than said holder and provided with a flange which is rigidly mounted on said holder, a tubular slide member rigidly mounted in said guide member bore, a tubular member slidably encompassing said slide member and slidably connected with said guide member, a tubular rotatable adjusting nut, a complementary

spiral connection between said adjusting nut and the tubular slide member, and a complementary flange and groove connection between said adjusting nut and the mouthpiece holder, said connection including a member encompassing said holder and which is provided with an annular shouldered portion which engages said guide member flange and an inwardly projecting thrust flange integral therewith.

4. A combined tuning device and joint of the character described comprising a tubular mouthpiece holder, a ring-like guide member of lesser diameter than said holder and provided with a right angular outwardly extending annular flange which is rigidly connected with one end of said holder, a tubular slide member mounted rigidly in the bore of said guide member, a tubular member slidably encompassing said slide member and slidably connected with said guide member, a tubular rotatable adjusting nut provided with an outwardly projecting annular flange adjacent one end thereof, a complementary spiral connection between said adjusting nut and the tubular slide member, and means forming an annular bearing groove for said adjusting nut flange to prevent longitudinal movement of said nut upon rotation thereof, said means comprising said guide member flange and a ring-like thrust member which is connected with the exterior of said mouthpiece holder.

ALLEN LOOMIS.
